FOLDING IRONING TABLE

Samuel J. Bailey, Nicholson, Pa.

Application November 1, 1932, Serial No. 640,801

2 Claims. (Cl. 68—10)

This invention relates to new and useful improvements in a folding ironing table. The invention has for an object the construction of a folding ironing table which is characterized by the provision of a pair of rear legs pivotally mounted upon a frame so that they may swing together and apart transversely relative to the ironing board, and the arrangement of pivotally supporting said frame upon the bottom of the board so that the legs may be moved flat against the bottom of the board or to depend therefrom.

The invention has for a still further object the arrangement of a pair of braces pivotally mounted intermediately of said legs and supported at intermediate points by links to the bottom of said board so as to be capable of assuming a rearward position past the dead center of the turning of the links to hold the pair of legs in a substantially vertical position.

Furthermore, the invention proposes the provision of a pair of crossed braces having one of their ends pivotally connected with the frame previously mentioned and the other ends pivotally mounted upon the pair of braces near the pivoted point with the pair of legs so as to cause the pair of legs to be pivoted slightly outwards so as to assume the vertical depending position.

The invention has for a still further object the construction of an article of the class described which is of simple, durable construction, dependable in use and efficient in operation and which can be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:—

Fig. 1 is a side elevational view of a device constructed according to this invention.

Fig. 2 is a horizontal sectional view taken on the line 2—2 of Fig. 1.

Fig. 3 is an end elevational view looking from the left hand end of Fig. 1.

Fig. 4 is a fragmentary sectional view taken on the line 4—4 of Fig. 1.

Fig. 5 is a bottom view of the device in a completely closed position.

Fig. 6 is a side elevational view similar to Fig. 1 but showing the device partially closed.

Fig. 7 is a sectional view taken on the line 7—7 of Fig. 6.

Reference numeral 10 indicates the board of the folding ironing table. A transverse frame 12 has ends 13 turned at right angles to the main portion thereof and pivotally supported upon angle members 14 secured upon the bottom of the board 10. A pair of rear legs 15 are pivotally supported at their upper ends by pintles 16 engaged through the frame 12. The arrangement allows the legs 15 to be pivoted together or apart while the pivoting of the frame 12 allows the legs 15 to assume positions flat against the bottom of the board 10 or depending as shown in Fig. 1.

A pair of braces 17 are pivoted at their rear ends intermediate the ends of the legs 15. At the front the braces 17 are pivotally connected with a pair of links 18. These links in turn are pivotally connected at their ends upon the bottom of the board 10. The parts are so proportioned that when the legs 15 slant slightly backwards from the vertical, as shown in Fig. 6 the free ends of the braces 17 are past the dead center of the links 18, figuring clockwise as seen in Figs. 1 and 6, so as to prevent any possibility of the legs 15 accidentally assuming their closed positions. The front ends of the braces 17 are beveled off at 19 so that these beveled edges may rest against the bottom of the board 10. As may be seen from inspecting Fig. 1, the links 18 are substantially in line with the braces 17 when the legs 15 are in their open positions, but any tendency for the legs 15 to close will tend to cause the ends 19 to press against the bottom of the table board 10. In order to close the legs 15 it is necessary that the ends 19 of the braces 17 be first drawn slightly downwards, that is, turned counter-clockwise in respect to the links 18.

A pair of cross braces 20 is pivotally connected at their top ends 21 upon the legs 15 and more particularly, concentric with the pivotal mounting of the legs 15. The braces 20 have their other ends 22 twisted at 90° and pivotally attached intermediate the ends of the braces 17 near the pivots of the braces 17 and the legs 15. Particular attention is drawn to Figs. 5 and 6 where it should be noted that as the legs 15 are moved to the closed position the braces 20 will extend the sum of the distance from the pivots of the legs 15 to the pivot of the legs to the braces 17 and the distance from the

pivots of the braces 17 with the legs 15 to the pivots of the brace ends 22. Consequently, since the ends 21 of the braces are pivotally mounted upon the frame 12 the ends 22 will move towards each other and close the legs 15 to positions parallel with each other as shown in Fig. 5.

But when the legs 15 are moved to the depending position the pivots of the ends 22 of the braces 20 will be moved closer to the pivots of the ends 21 as clearly shown in Fig. 1, which will cause the ends 22 to move apart from each other and spread the legs 15 as shown in Fig. 3. A front leg 23 is pivotally mounted at one end 24 upon the bottom of the board 10. Wire connecting links 25 pivotally connect with the leg 23 and with the legs 15 so as to restrain the leg 23 from closing flat against the bottom of the board 10 when the legs 15 are in the depending position. The wire links 25 hold the leg 23 in the open position when the legs 15 are open. A chain 26 is connected between the pair of braces 17 and serves to limit anti-clockwise turning of the leg 23, that is, it serves to act to maintain the device in the open position.

The operation of the device can readily be understood from examining Figs. 1, 5 and 6. To close the folding wire table from the open position shown in Fig. 1 it is first necessary that the ends 19 of the braces 17 be slightly drawn downwards and then the braces 17 be pulled around to swing on the links 18 as pivots. This causes the legs 15 to start moving to the closing position and as the legs 15 move, the links 25 will transmit this motion to the front leg 23. The legs 15, when in the open position are inclined outwards, as shown in Fig. 3, but as they assume the closed positions the cross braces 20 will automatically draw them together to substantially parallel positions as shown in Fig. 5, the object being that the legs be completely folded within the side limits of the board 10. A main feature is the fact that the legs 15 may pivot towards each other and at the frame 12 may allow the legs to simultaneously pivot flat against the bottom of the board 10 and to the depending position. Another main feature is the arrangement of the cross braces 20 which act between the pivoting frame 12 and the braces 17 in a manner so as to automatically cause the sliding of the legs 15 as the table assumes the open position.

While I have shown and described the pre-

ferred embodiment of my invention, it is to be understood that I do not limit myself to the precise construction herein disclosed and the right is reserved to all changes and modifications coming within the scope of the invention as defined in the appended claims.

Having thus described my invention, what I claim is new, and desire to secure by United States Letters Patent is:—

1. In a folding ironing table, a board, a transverse frame pivoted on the bottom thereof, a pair of legs pivoted on said frame for swinging together and apart and which upon turning of the frame moves to a position flat against the bottom of the board or to a depending position, a pair of braces pivotally mounted at one of their ends intermediate the ends of said legs, a pair of links pivotally mounted intermediate the ends of said braces and on the bottom of said board so that the legs are limited to substantially the vertical position or to a position flat against the bottom of said board, and a pair of cross braces pivotally mounted at one of their ends upon said legs and at their other ends upon said braces at points intermediate the pivot points of the braces with the legs and with said links, said cross braces having intermediate twists so that the pivoted ends are at right angles to each other.

2. In a folding ironing table, a board, a transverse frame pivoted on the bottom thereof, a pair of legs pivoted on said frame for swinging together and apart and which upon turning of the frame moves to a position flat against the bottom of the board or to a depending position, a pair of braces pivotally mounted at one of their ends intermediate the ends of said legs, a pair of links pivotally mounted intermediate the ends of said braces and on the bottom of said board so that the legs are limited to substantially the vertical position or to a position flat against the bottom of said board, a pair of cross braces pivotally mounted at one of their ends upon said legs and at their other ends upon said braces at points intermediate the pivot points of the braces with the legs and with said links, a front leg pivotally mounted upon the bottom of said board, a chain connected between said pair of braces, and rods connected between said front legs and said rear pair of legs to cause the legs to move in unison from the open to the closed position.

SAMUEL J. BAILEY.
